WIRE CLOTH OR FABRIC

Application filed February 13, 1931. Serial No. 515,490.

This invention relates to woven wire cloth or fabric, such as is used on papermaking machines, and the principal object of our invention is to provide a joining of the ends 5 of the cloth or fabric in such a manner as to obtain a maximum of strength and a minimum drainage obstruction, which is essential for the successful operation under the exacting requirements to which a wire cloth or fabric of this nature is subjected.

A further object is to make a joining of the ends of the cloth or fabric in such a manner as to obtain a uniform impervious cloth or fabric at the point of joining.

15 A further object is to make a joining of the ends of the cloth or fabric in such a manner that such joining or uniting is intermediate the top and bottom surface planes of the fabric.

20 A further object is to make a joining of the ends of the cloth or fabric by uniting the protruding ends of the warp wires of one end of the cloth or fabric, intermediate the marginal weft wires of the respective joined portions, to the opposite end of such wire cloth or fabric.

With the foregoing and other objects in view as will appear as the description proceeds, the invention consists of the novel construction, combination and arrangement of co-operating elements as hereinafter more specifically set forth, claimed and shown in the accompanying drawing forming a part of the present application, in which:

35 Fig. 1 and Fig. 2 are longitudinal section views of the respective ends of the wire cloth or fabric which are to be joined, and

Fig. 3 is a longitudinal section view of the respective ends of the wire cloth or fabric 40 showing them as joined.

Like numerals of reference designate corresponding parts throughout the different views.

Referring to Fig. 1, this end of the wire cloth or fabric is characterized by the fact that the warp wires 5 and 6 are securely united, in their woven position, to the marginal weft wire 4, by soldering, welding, fusing, brazing, or other like manner. After

ing ends of the wires 5 and 6 are cut off as on a line A—A of Fig. 1, which line of cutting is substantially flush with the outer edge of the marginal wire 4.

Referring to Fig. 2, this end of the wire cloth or fabric is characterized by the fact that the warp wires 5' and 6' are securely united, in their woven position, to the weft wire 7, which is the next to the marginal weft wire 8, by soldering, welding, fusing, brazing, or other like manner. After the wires 7, 5' and 6' are united, the protruding ends of the wires 5' and 6' are cut off as on a line B—B of Fig. 2, which line of cutting is substantially flush with the inner edge of the marginal wire 8. Thus, the weft wire 7 becomes the marginal weft wire of this portion of fabric.

Referring to Fig. 3, we have shown the free ends of the warp wires 5' and 6' as 70 abutting the ends of the warp wires 5 and 6 respectively, on the line C—C. While held in such abutted position, these ends are securely united to provide an integral connection between the respective warp wires 5—5' 75 and the weft wire 4 and between the respective warp wires 6—6' and the weft wire 4, by soldering, welding, fusing or brazing or other like manner. This provides a continuity of the wires 5—5' and 6—6' in uniform woven 80 relationship, with a minimum drainage obstruction intermediate the weft or warp wires at the point of joining. We do not wish to be limited to the warp wires 5' and 6' having to precisely abut their respective warp wires 5 and 6. The protruding ends of the warp wires 5' and 6' may abut and contact with the marginal weft wire 4 intermediate the warp wires 5 and 6 either vertically or laterally.

By cutting the portion of fabric as shown in Fig. 1, on the line A—A, where the warp wires 5 and 6 are in converging relation to each other, and, by cutting the portion of fabric as shown in Fig. 2, on the line B—B, where the warp wires 5' and 6' are in diverging 95 relationship to each other, the warp wires 5, 6, 5' and 6' are cut on an angle and consequently the abutting faces of such warp wires provide a greater area than the normal cross-section area thereof. Furthermore, the 100

contacting faces thereof are preferably cut in parallel planes and the ends of the warp wires to be joined are intermediate and in spaced relation from the top and bottom surface planes of the respective portions of fabric, when the warp wires 5 and 5' and 6 and 6' are joined respectively. By joining the respective warp wires, as on the line C—C of Fig. 3 and in the manner as hereinbefore described, the respective contacting warp wires are in direct longitudinal alignment with each other and form an uninterrupted uniform mesh formation at the point of joining.

15 The foregoing specification and annexed drawing disclose the preferred embodiment of our invention; but it is to be understood that minor changes may be resorted to in the commercial adaptation of our invention without departing from the scope of the invention as hereinafter claimed.

What we claim as new is:

1. Wire cloth or fabric, formed from portions woven of warp and weft wires; the ends 25 of the respective sets of wires, forming the warp wires of one portion, having their ends cut at a point where they are in diverging relationship to each other; the ends of the respective sets of wires, forming the warp 30 wires of the other portion, having their ends cut at a point where they are in converging relationship to each other; the ends of said portions being united, intermediate the marginal weft wires of said portions.

35 2. Wire cloth or fabric, formed from portions woven of warp and weft wires; the respective joining ends of the warp wires of said portions being in direct longitudinal alignment with each other; the ends of said portions being united, intermediate and in spaced relationship from the surface planes of said portions.

40 3. Wire cloth or fabric, formed from portions woven of warp and weft wires; the ends 45 of the respective sets of wires, forming the warp wires of one portion, having their ends cut at a point where they are in diverging relationship to each other; the ends of the respective sets of wires, forming the warp 50 wires of the other portion, having their ends cut at a point where they are in converging relationship to each other; the ends of said portions being united, intermediate the marginal weft wires of said portions, together in 55 mesh formation substantially uniform with said portions.

60 4. Wire cloth or fabric, formed from portions woven of warp and weft wires; the ends 65 of the respective sets of wires, forming the warp wires of one portion, having their ends cut at a point where they are in diverging relationship to each other; the ends of the respective sets of wires, forming the warp wires of the other portion, having their ends cut at 70 a point where they are in converging relation-

ship to each other; the ends of said portions being united, intermediate and in spaced relationship from the surface planes of said portions, together in mesh formation substantially uniform with said portions.

75 5. Wire cloth or fabric, formed from portions woven of warp and weft wires; the ends of the respective sets of wires, forming the warp wires of one portion, having their ends cut at a point where they are in diverging relationship to each other; the ends of the respective sets of wires, forming the warp wires of the other portion, having their ends cut at a point where they are in converging 80 relationship to each other; the ends of said portions being united, intermediate the marginal weft wires of said portions, together in a pervious structural formation substantially uniform with the pervious structural formation of said portions.

85 6. Wire cloth or fabric, formed from portions woven of warp and weft wires; the ends of the respective sets of wires, forming the warp wires of one portion, having their ends cut at a point where they are in diverging 90 relationship to each other; the ends of the respective sets of wires, forming the warp wires of the other portion, having their ends cut at a point where they are in converging relationship to each other; the ends of said 95 portions being united, intermediate and in spaced relationship from the surface planes of said portions, together in a pervious structural formation substantially uniform with the pervious structural formation of said portions.

In testimony whereof, I affix my signature.

JOHN ROBERT BUCHANAN.

In testimony whereof, I affix my signature.

THOMAS MICHAEL CRAY.
